UNITED STATES PATENT OFFICE.

THOMAS W. JOHNS, OF BROOKLYN, NEW YORK.

CASTING MECHANISM FOR TYPOGRAPHICAL MACHINES.

1,340,613.

Specification of Letters Patent. Patented May 18, 1920.

Application filed September 12, 1918. Serial No. 253,722.

To all whom it may concern:

Be it known that I, THOMAS W. JOHNS, a citizen of the United States, residing at Brooklyn, in the county of Kings and State of New York, have invented new and useful Improvements in Casting Mechanism for Typographical Machines, of which the following is a specification.

This invention relates to improvements in line casting machines, and more especially to those of the linotype class wherein an assembled line of matrices is presented to a mold and the slug is cast in the mold, the slug being formed with a character-bearing edge which conforms to the characters borne by the matrices.

The primary object of the invention is to provide a novel and improved mold, coöperating mouthpiece for the metal pot, and ejector, whereby slugs of different lengths may be produced with facility, requiring minimum labor and time in the adjustment of the machine. Another object is to provide novel and improved trimming means for the slug which is capable, without adjustment or change, of trimming the slugs of different lengths cast in the mold.

To these and other ends, the invention consists in certain improvements, and combinations and arrangements of parts, all as will be hereinafter more fully described, the novel features being pointed out particularly in the claims at the end of the specification.

35 In the accompanying drawings:

Figure 1 is a side elevation of the slug ejecting and trimming mechanism constructed in accordance with the present invention, the same being shown in coöperative relation with a mold which also embodies the present invention.

Fig. 2 is an end elevation of the mechanisms shown in Fig. 1 as viewed from the left.

45 Fig. 3 is a top plan view of the trimming mechanism and adjacent portions of the ejecting means and the mold.

Fig. 4 is a face view of the upper portion of the mold disk showing a mold embodying the present invention in elevation.

Fig. 5 is a collective view showing the elements or members of a mold constructed in accordance with the present invention.

Fig. 6 is a perspective view of the mold assembled, showing the manner in which the ejector operates therethrough.

Fig. 7 represents, on an enlarged scale, a section taken through the mold and the mouthpiece of the metal pot, the latter being shown in engagement with the mold, and 60

Fig. 8 represents a transverse section through the mold showing the mouthpiece and a part of the spout of the metal pot in section.

Fig. 9 represents an elevation of a portion of the mouthpiece of the metal pot as viewed from the front, and 65

Fig. 10 represents a section on the line 10—10 of Fig. 9.

Similar parts are designated by the same 70 reference characters in the several views.

The present invention is applicable generally to line casting machines of different types capable of casting slugs having different characters along an edge thereof. The 75 invention is particularly applicable to machines of the linotype class, it being so shown in the present instance. It is to be understood, however, that the invention is not restricted to the precise construction 80 shown as equivalent constructions are contemplated and will be included within the scope of the claims.

In the present instance, 1 represents the so-called mold disk or wheel which is commonly used in machines of the linotype class, this mold disk serving to support one or more molds and being operative to set such mold or molds in position for casting and also in position for ejection of the cast slug 90 therefrom. The improved mold provided by the present invention comprises a mold body 2 which is fixed to the face of the mold disk and is provided with suitable grooves 3 to receive the lower lugs of the line of matrices M when the latter are brought to a position in front of the mold, a mold cap 4, and liners 5 and 6. According to the present invention, one of the elements or members of the mold is provided 100 with longitudinally spaced and transversely extending ribs or partitions which, when the members of the mold are assembled, project into the cavity of the mold in which the slug is cast and thus determine the length 105 of the part of the mold cavity to receive the type metal. Preferably, and as shown, an auxiliary liner or equivalent part 7 is used, this auxiliary liner having plain or flat ends to fit between the mold cap 4 and the liners 110 5 and 6, and the auxiliary liner being formed with ribs 8 which, when the auxiliary liner

is in position, project into the mold cavity. The elements of the mold are clamped together by any suitable means, a clamping screw 9 being shown for this purpose in the present instance. The ribs 8 of the auxiliary liner which extend entirely across from front to back of the mold are preferably spaced longitudinally of the mold at regular intervals with regard to the graduated measures of the length of a line. It is most advantageous to space the ribs 8 at intervals of two ems, the length of line being usually measured in ems. It will be understood that ordinarily a number of auxiliary liners will be provided, each of these auxiliary liners having a different number of ribs, but the ribs on the different liners are similarly located in a direction longitudinally of the mold when the different liners are applied thereto. By referring to Fig. 4 it will be observed that the left-hand portion of the mold cavity designated generally as 10 is intersected by the ribs 8, the right-hand end 10^a of the mold cavity being unobstructed by these ribs. The length of the slug cast in the right-hand portion 10^a of the mold cavity will, in consequence, correspond to the distance between the inner edge of the right-hand liner 6 and the adjacent rib 8 on the auxiliary liner. By using an auxiliary liner having one less rib, that is to say, with the right-hand rib 8 omitted, the length of the portion 10^a of the mold cavity and, in consequence, the length of the slug cast in the mold will be increased two ems. By using other auxiliary liners having greater numbers of the ribs 8 omitted from the right-hand portion thereof, the length of the slug can be increased to different line measures varying by intervals of two ems. Likewise, by using auxiliary liners having greater numbers of ribs on the right-hand portion thereof, the length of the portion 10^a of the mold cavity and, in consequence, the length of the slug cast therein may be reduced to measures varying by two ems. In this way, a slug having any desired length within the capacity of the machine measured in even numbers of ems may be produced using a standard right-hand liner 6. Slugs measured in odd numbers of ems may be produced in conjunction with the auxiliary ribbed liners by substituting a shorter end liner 6^a, this end liner 6^a being one em shorter than the standard end liner 6. Likewise, lines varying in half em lengths can be obtained by the use of the different auxiliary ribbed liners by using a right-hand end liner 6^b of intermediate length, this end liner 6^b being half an em shorter than the standard end liner 6 and half an em longer than the shortest end liner 6^a.

According to the present invention, the introduction of an auxiliary liner having the appropriate number of ribs thereon to produce a slug of the desired length will automatically determine the length of the mold cavity utilized in the casting of the slug. This result is accomplished by the aid of a mouthpiece 11 for the metal pot which mouthpiece is provided with the usual metal-injecting orifices 12 for introducing the metal into the right-hand portion 10^a of the mold cavity, these orifices 12 being usually spaced at distances of one em each, and an additional orifice 13 is provided beyond the right-hand end of the orifices 12 to introduce type metal into the portion 10^a of the mold cavity which is extended when the shortest end liner 6^a is used. Toward the left-hand end of the mouthpiece 11 the latter is provided with pairs of orifices 14, each pair of these orifices 14 being spaced apart at distances of two ems. Each pair of the orifices 14 is so located in the mouthpiece of the metal pot that when the latter comes into engagement with the rear face of the mold, each rib 8 of the auxiliary liner will be opposite to a corresponding pair of these orifices 14 and will close them, the auxiliary liners for the casting of the slugs of longer lengths and which have one or more of the ribs 8 omitted therefrom causing corresponding numbers of these pairs of orifices 14 to be uncovered. The orifices 14 which are covered by the ribs 8 of the auxiliary liner are closed thereby, and hence no metal from the metal pot can enter the portions of the mold cavity occupied by such ribs. Metal, however, will be permitted to enter the mold cavity through the usual orifices 12 and through such pairs of the orifices 14 as are uncovered by the omitted rib or ribs 8 of the auxiliary liners and also through the additional single orifice 13 when the shortest end liner 6^a is used for the casting of slugs of odd lengths. The pairs of orifices 14 in the mouthpiece are preferably located directly above one another and, as shown in Fig. 8, the upper orifice diverges laterally with respect to the lower orifice of the respective pair in order that the metal from the upper and lower orifices of each pair will strike the character faces of the matrices at different points spaced one em along the length of the line, although the pairs of orifices are spaced two ems apart. In consequence, the metal will be evenly distributed along the length of the line of matrices, while the two-em spacing of the orifices enables the tongues of the ejector blade to be made relatively wide and strong. The mouthpiece 11 may be fitted in a suitable way in the spout 15 of the metal pot and the metal pot may be of the type usually employed in machines of the linotype class for forcing the molten type metal into the mold cavity and against the character faces of the line of matrices.

According to the present invention, the introduction of an auxiliary liner having

presented to the front face of the mold. By using auxiliary liners having transverse ribs of different numbers arranged at graduated intervals longitudinally thereof in conjunction with a mouthpiece having metal-injecting orifices correspondingly spaced, the length of the mold cavity which receives the molten type metal is automatically determined by the number of ribs on the auxiliary liner used, the ribs on the liner blocking the orifices of the mouthpiece which would otherwise introduce type metal into those portions of the mold cavity occupied by the ribs.

The present invention provides a novel and improved ejector for removing the slug from the mold, this same ejector serving to remove the slugs irrespective of the lengths thereof. The ejector, as shown, comprises a blade 16 having a tongue 17 of a width corresponding, preferably, to the slug of shortest length which it may be desired to cast in the mold, and a number of tongues 18, the tongue 17 of the ejector blade being operative through the right-hand portion 10^a of the mold cavity, and the tongues 18 being operative through the recesses which are formed between the ribs 8 of the auxiliary liner. The ejector blade 16 is attached to a slide 19 which may correspond to the ejector slide commonly used in machines of the linotype class, the ejector slide being reciprocated at appropriate intervals by a link 20 which is operatively connected to an arm 21, the latter being actuated or controlled by a suitable cam. The ejector blade 16 is guided to reciprocate in alignment with the mold cavity and the tongues 17 and 18 thereon will operate through the mold cavity, including the portion in which the slug is cast and also the recesses which are formed between the ribs 8 of the auxiliary liner irrespective of the length of the slug cast in the mold, and hence a single ejector blade is capable of ejecting the shortest slugs, the longest slugs within the capacity of the mold, and slugs of all intermediate lengths.

The present invention also provides means for trimming the flat sides of the slugs cast in the mold irrespective of whether the end liner 6^a or the end liner 6^b is used. As shown, the trimming mechanism comprises a vertical channel or chute 23 which is preferably mounted on the usual column of the main frame of the machine to enable the vise frame to be swung open or closed without disturbing the trimming mechanism. This channel 23 occupies a position immediately in front of the mold when the latter is brought to the slug-ejecting position and the ejector blade 16 preferably has a stroke just sufficient to carry it through the mold, pushing the slug from the mold in advance of the blade and into the channel 23. The

trimming means comprises a stationary trimming knife 24 which is arranged at one side of the chute 23 and a cutter 25 which is arranged at the opposite side of the chute, the cutter 25 being shown in the form of a revolving toothed cutter and it is adapted to trim the upper side of the slug which usually has transverse ribs thereon corresponding to transverse grooves which are formed in the upper wall of the mold cavity. The cutter 25 is carried by a lever 26, the latter being pivoted at 27 to a stationary part of the machine frame, and means is provided at the upper end of the lever 26 to set it in different positions whereby the distance between the knife 24 and the cutter 25 may be varied to trim slugs to different thicknesses. As shown, a graduated eccentric or cam 28 is pivoted at 29 to a suitable stationary part of the machine frame, and the upper end of the lever 26 is held against the eccentric or cam surface of the cam 28 by a spring 30. Rotation of the cam or eccentric 28 will set the cutter 25 at different distances from the knife or cutter 24 to conform to slugs of different thicknesses. In using a rotary toothed cutter, as shown, the same may be driven through gears 31, a flexible shaft 32, and a belt pulley 33, the latter being arranged in the present instance to coöperate with a belt 34 which passes over pulleys 35 and 36. Each slug after ejection from the mold is held above the cutters 24 and 25 by a spring 37 which may be attached to the lever 26. Feeding of the slug endwise between the cutters 24 and 25 is effected by a vertically reciprocatory slide 38 having a projection 39 thereon which is arranged to engage the upper end of the slug, the slide 38 being operated by a rack 40 thereon which coöperates with a pinion 41, the pinion 41 being connected to a pinion 42 and the latter coöperating with a rack 43 on a forwardly and rearwardly moving rack bar 44, this rack bar being conveniently connected at 45 to the arm 21 which actuates the ejector slide. After trimming, the slug descends by gravity into a galley chute 46. In Figs. 1 and 2, the slugs are designated "S," one slug occupying a position above the trimming cutters, and another being shown below the cutters. In Fig. 1, a slug is shown in the galley chute. By trimming the slugs by a trimming mechanism as described, it is unnecessary to adjust or otherwise change the setting of the trimming mechanism when the right-hand liners 6^a or 6^b are substituted for the usual constant end liner 6, adjustment of the trimming mechanism being necessary only when the thickness of the slug is to be changed, and such adjustment can be made easily and quickly by simply rotating the cam or eccentric 28.

The present invention provides a mold

and coöperative ejector and trimming mechanism which are particularly useful in the casting of type slugs for advertising or display matter, or in other connections where 5 numerous changes in the length or thickness of the slugs is required. The mold can be quickly and easily changed to cast slugs of different lengths by inserting auxiliary liners having the appropriate number of 10 ribs thereon, and the particular auxiliary liner used will, in each instance, automatically determine the number of orifices in the mouthpiece of the metal pot through which type metal will be ejected into the 15 mold cavity. Also, the same ejector blade serves to remove the slugs from the mold irrespective of the varying lengths of the slugs, and hence changing of the ejector to conform to the length of the slug is unne- 20 cessary.

Preferably, and as shown, the rear edge of the auxiliary liner 7 is formed with an up-turned flange 7^a, and the rear edge of the mold cap 4 is correspondingly cut away, as 25 shown in Fig. 8, thus enabling the mold cap to be removed without requiring removal of the mold body from the mold disk. Obviously, the ribs 8 may be formed on the lower faces of the mold caps, in which case 30 the use of auxiliary liners would be unnecessary, and, furthermore, both knives or cutters of the trimming mechanism may be composed of plain stationary blades like the blade 24.

35 I claim as my invention:

1. In casting mechanism for typographical machines, a slug casting mold comprising a body, end liners, and a cap forming a cavity for the casting of the slug therein, 40 and a member having longitudinally spaced portions adapted to project transversely into said cavity between said liners and toward one end of the mold cavity to partially close and thereby reduce the length of said 45 cavity, in combination with a metal pot mouthpiece having longitudinally spaced metal injecting orifices adapted to register with and to be closed by said longitudinally spaced portions of said member.

50 2. In casting mechanism for typographical machines, a slug casting mold having a cavity adapted to cast a slug therein and longitudinally spaced transversely extending ribs projecting into said cavity to reduce the slug casting length thereof, in combination with a metal pot mouthpiece having metal injecting orifices adapted to be covered and closed by said ribs.

55 3. In casting mechanism for typographical machines, a slug casting mold having a cavity for the casting of slugs therein, and a plurality of ribs adapted to project into said cavity, said ribs being spaced equidistantly longitudinally of said cavity and ex- 60 tending transversely across the same, in

combination with a metal pot mouthpiece having metal injecting orifices adapted to register with and to be closed by said ribs.

4. In casting mechanism for typographical machines, a slug casting mold having a body forming a cavity for the casting of slugs therein, and a cap for closing the top of said cavity, and a liner adapted to be clamped at its ends between said body and cap and provided with longitudinally spaced transversely extending ribs arranged to project into said cavity to the full depth and width thereof, in combination with a metal pot mouthpiece having longitudinally spaced metal injecting orifices arranged to register with and adapted to be closed by said ribs.

5. In casting mechanism for typographical machines, a slug casting mold comprising a body, a cap, and end liners coöperative to form a mold cavity, and means located between said end liners for closing said cavity toward one end thereof and thus reduce the length of the slug cast therein in accordance with regular line measurements, the end liner at the opposite end of the mold cavity being interchangeable with other end liners of different lengths to vary the lengths of the slugs in accordance with odd or intermediate line measurements.

6. In casting mechanism for typographical machines, a slug casting mold having a cavity for the casting of slugs therein, ribs spaced longitudinally in accordance with graduations of regular line measurements 100 and adapted to project into said cavity toward one end thereof, and interchangeable end liners adapted to determine the opposite end of said cavity, in combination with a metal pot mouthpiece having metal injecting orifices spaced longitudinally in accordance with regular line measurements and adapted to register with and to be closed by 105 said ribs.

7. In casting mechanism for typographical machines, a slug casting mold having a cavity for the casting of a slug therein and having a member provided with a plurality of ribs spaced longitudinally and adapted to project into said cavity to determine the 110 slug casting length thereof, in combination with a metal pot mouthpiece having metal-injecting orifices spaced in accordance with the spacing of said ribs and adapted to be 115 covered and closed by said ribs.

8. In casting mechanism for typographical machines, a slug casting mold adapted to interchangeably receive members having respectively different numbers of ribs spaced uniformly in a direction longitudinally 125 thereof and adapted to project into said cavity to determine the slug casting length thereof, in combination with a metal pot mouthpiece having metal orifices for injecting metal into said cavity, said orifices of 130

the mouthpiece being spaced and located to register with the respective ribs of said members.

9. In casting mechanism for typographical machines, a slug casting mold having a cavity for the casting of slugs therein and a member having longitudinally spaced ribs adapted to project into said cavity to determine the slug casting length thereof; and,
- 10 a metal pot mouthpiece having pairs of metal-injecting orifices arranged to register respectively with said ribs, one orifice of each pair of orifices diverging laterally with respect to the other orifice of the respective pair.
11. In casting mechanism for typographical machines, a mold having a cavity for the casting of slugs therein and a member having ribs adapted to project into said cavity, toward one end thereof to close said end of the cavity and to determine the length of the slug to be cast in the opposite end of the cavity, said ribs being spaced equidistantly longitudinally, in combination with an ejector blade having equidistantly spaced longitudinal slots to form tongues

operative through the equal-size spaces formed in the respective end of the mold cavity by said ribs, and also through the space in which the slug is to be cast. 30

12. In casting mechanism for typographical machines, a mold having a cavity for the casting of slugs therein and adapted to receive members having respectively similarly and equidistantly spaced 35 ribs thereon adapted to project across said cavity to close said cavity toward one end thereof, and to determine the length of the slugs to be cast in the other end of the cavity, in combination with an ejector blade slotted longitudinally at points in register with the ribs of the different members, thus providing tongues operative through the slug portion of said cavity, and also the spaces of 40 said ribs.

In testimony whereof I have hereunto set my hand in presence of two subscribing witnesses.

THOMAS W. JOHNS.
